Patented June 13, 1922.

UNITED STATES PATENT OFFICE.

ALBERTO I. WOODRING, OF WATERLOO, IOWA, ASSIGNOR, BY MESNE ASSIGNMENTS,
TO NATIONAL SAFETY DEVICES COMPANY, OF WATERLOO, IOWA.

SIGNAL-GOVERNING APPARATUS.

1,419,435.

Specification of Letters Patent. Patented June 13, 1922.

Application filed January 19, 1922. Serial No. 530,315.

To all whom it may concern:

Be it known that I, ALBERTO I. WOODRING, a citizen of the United States of America, and a resident of Waterloo, Blackhawk, 5 County, Iowa, have invented certain new and useful Improvements in Signal-Governing Apparatus, of which the following is a specification.

My invention relates to improvements in 10 signal governing apparatus, and particularly to means for actuating a whistle or other signal upon a locomotive or the like with a predetermined number of different impulses according to the requirement of a 15 designated code.

One object of my improvements is to provide mechanism suitable to be actuated directly by means of a relay of fluid-pressure to thereby avoid muscular strain, reserving 20 to the operator only means for producing an initiatory setting action therein, resulting in the desired sequence of subsidiary actions.

Another object is to include means in the 25 operating devices for the change or adjustment of tension and of speed of the moving parts, as requisite under different conditions of service.

Another object is to add means operative 30 automatically to initiate the desired train of actions in operating the signal without attention of a special operator, while the apparatus is being translated with the vehicle relative to designated localities, such as while approaching a highway or other place.

35 Other objects will be more specifically described and pointed out hereafter in the following description and claims.

These objects have been successfully accomplished by the means hereinafter described 40 and claimed, and which are illustrated in the accompanying drawings in which Fig. 1 is a front elevation of my improved signal governing device with parts broken away. Fig. 2 is a vertical medial cross section taken through the spring-barrel and the dash-pot, with other parts shown in elevation. Fig. 3 is a fragmentary end elevation of certain parts shown in said Fig. 2, and Fig. 4 is a fragmentary elevation of 45 the opposite part of said spring-barrel from that shown in Figs. 2 and 3. Fig. 5 is a longitudinal horizontal section of the cylinder and moving parts therein for relaying fluid-pressure therein for positively actuating 50 the signal. Fig. 6 is a longitudinal

horizontal section of another cylinder with moving parts therein for relaying fluid-pressure to operate the cam-bearing rock-body of the device.

This device embodies several improvements upon signal governing apparatus which are shown and claimed in my preceding applications for patents, Ser. Nos. 481,986 and 520,918.

Primarily, this apparatus is particularly 65 designed for convenient functioning in operating a whistle signal on any vehicle such as a locomotive whether steam or electric, and which also transports some suitable source of fluid-pressure. The purpose is to 70 not only relieve the engineer from responsibility of personally actuating the whistle signal with a desired number of actuations and intervals between actuations so that he may more easily keep his attention upon 75 other necessary and simultaneous employment, but also to relay the proper amount of fluid pressure to effect the forcible operation of the signal without excessive muscular strain, leaving it necessary merely to manually 80 initiate the desired train of actions by a single light power impulse.

Furthermore, the mechanism is so designed as to obviate any uncertainties or defects in the operation such as is incident 85 to all hand operations, to thereby produce distinct, fully sustained, and properly timed actuations of the signal as also of the intervals between the actuation.

The numeral 1 denotes an ordinary steam 90 sounded whistle such as is usually used on locomotives, although compressed air may be used for the purpose, and containing a valve-chamber with a valve therein not shown, having a projecting valve-stem 2 operated 95 by a projection on a pivoted arm 3 to whose upper free end is connected a link 4.

The principal operating element of this device is a rock-body 19 secured upon one end of a rock-shaft 20 by means of a nut 25 100 and a locking pin 26, said rock-body being a disk of which a portion of the circumferential periphery is depressed leaving, however, a number of spaced cam-projections of different widths and separated by different widths of intervals. In the instance illustrated, one pair 23 and 24 of the projections are the same width but of greater width than the width of the other projections 21 and 22. This is to conform to the present 110

railroad signaling code wherein the signal for approaching a highway is given in intermittent blasts, that is, a blast of two seconds duration followed by another of 5 two seconds durations after an interval of one second, the second blast being followed by a one second interval, with following two blasts of the whistle of one second duration each, separated by one second interval, a 10 total of nine seconds in all.

The numeral 32 denotes a spring-barrel with a connected dash-pot 30, and the numerals 51 and 80 denote cylinders positioned horizontally above and below said spring-barrel, all said devices being suspended from an elevated fixture 27 having a depending bearing socket within which a diminished part of a projection 28 is mounted for rocking adjustment and secured by a set-screw 20 29. The interior of the spring barrel 32 has a centrally orificed diaphragm or partition which seats the inner end of the rock-shaft 20, the latter having on said end a crank 35 provided with a pin and the latter connected 25 by a pitman 36 to a piston 37 with ball-valve 37' within the dash-pot 30 which, when the shaft rocks, bears against oil contents of the dash-pot to produce a cushioning effect at each limit of the rocking-movements of the 30 rock-body 19. 38 is a hand-wheel for turning a screw governing the flow through a bypass 38' leading from above the piston 37 to the bottom of the dash pot 30. The numeral 33 denotes a cylinder which is removably fitted in the barrel 32, and has a centrally orificed head 34 of greater exterior diameter than said barrel, and the circumferential edge of this head has gear-teeth.

Referring to said Fig. 4, the numeral 127 40 denotes a small flat plate mounted upon one side of the barrel 32 by means of screws 125 traversing a longitudinal slot 126, and the outer end of said plate has a number of spaced longitudinally directed detents 128 45 fitting the interspaces of teeth on the head 34. A helical spring 31 is mounted within the cylinder 33 around the shaft 20 with its outer end secured to the cylinder and its inner end secured to said shaft. Said detented plate 127 is employed in the adjustment of the tension of said spring, its teeth 128 being inserted between the teeth on the head 34 when the latter has been rocked sufficiently in a desired direction. When the 50 screws 125 have been loosened, the slot 126 permits sliding of the plate 127 to detach its teeth from the head 34 during said process of adjustment.

The numeral 130 denotes a plate secured 60 to the barrel 32 opposite said plate 127 by means of screws 129, and this plate carries an integral horizontal arm 72, whose outer end is formed with an elongated orificed bearing part to receive a diminished part of 65 a short rock-shaft 71, one end of which has

an upright arm 70 with a flattened extremity. On the other end of said shaft is fixedly secured the upper end of a depending arm 73 which has offset parts or stops 76 at opposite sides of its lower extremity. The numeral 70 74 denotes a pair of parallel bars between whose ends adjacent the rock-body 19 is mounted an anti-friction roller 78 on pintles 77, said roller being positioned within the path of movement of said projections 21 to 75 24 inclusive. The opposite ends of said bars are pivotally mounted upon opposite sides of the arm 73 on pintles 75, and these ends of said bars have curved parts above and adapted to ride upon the stop parts 76. 80

Referring to Fig. 6, the cylinder 80 contains a reciprocatory imperforate piston 85 mounted upon the rod 86 which projects from one head thereof, and a coiled spring 87 is mounted within said cylinder and engaged between the piston and the head of the cylinder around said rod 86. Said rod 86 is of rectangular cross section and on its outwardly projecting end 45 a rectangular sleeve 44 is secured adjustably by means of a set-screw 46. On the opposite side from said screw said sleeve is provided with a projecting boss having a diminished cylindrical pindle 43 passed through a bearing orifice in one end of a connecting-rod 42. The other end of said rod has a pindle 41 mounted loosely in a bearing opening in the rock-body 19 and secured thereto by a nut. In the body of the cylinder 80 is formed a longitudinal passage 81 communicating with the interior of the cylinder at one end by way of an opening 83, and the area of the latter is controlled by means of a screw 84 to adjustably vary the amount of entering air under pressure. The other end of the 105 passage 81 communicates through a port 82 and by way of an elbow-coupling 88 and short pipe 89 with the upper part of a valve-chamber 90 containing a two-way check-valve, and at one side of said chamber a 110 short pipe 91 includes an operating valve 112 having a valve-rocking handle 111. The pipe 91 leads by way of a coupling 116 to a pipe 117 leading to a source of fluid-pressure supply, such as compressed air not shown. 115 Within the chamber 112 is mounted a three-way plug-valve for effecting or cutting off communication between the two-way check-valve 90 and said air supply. The chamber 112 has an exhaust-port 113 which may register with one opening of the passages through the three-way valve, when the handle 111 is rocked to cause the valve to close the communication between the valve-chamber 90 and pipe 117, serving to exhaust 125 compressed air from the cylinder 80.

The upper cylinder 51 is constructed of two aligned connected parts separated by an orificed diaphragm containing a removable threaded centrally orificed plug-bearing for 130

a diminished part of a squared piston-rod 9, said rod carrying an imperforate piston 65 within and fitting the left-hand part of the cylinder. A coiled spring 66 is mounted 5 in this part of the cylinder around the rod 9 and engaged between the outer end of the cylinder and said piston. The right-hand end of the cylinder is divided into two compartments by means of a centrally orificed 10 partition 59 and 56, the said orifice therein numbered 60 being larger in diameter than a received part of a valve-rod 57. Within the chamber next to the right of the partition 64 a valve-head 61 is secured on the rod 15 57, and a short coiled spring 62 is mounted in a socket sleeve projecting from the plug in the partition 64 and is engaged between said socket and said valve-head. Within the compartment at the right of the partition 59 is positioned a hollow rod 54 alined 20 with the convex end of the rod 57, and said rod 54 traverses a bearing opening in the right cylinder-head and has a port 55 therein leading from its hollow to the atmosphere, 25 and the inner end of the rod 54 is cupped to fit the convex end of the rod 57. The outwardly projecting extremity of the rod 54 is threaded to receive a socketed hard steel head 52 whose outer curved end is contacted 30 by the flattened extremity of the arm 70. Said head 52 may be adjustably secured by means of a set-screw 53 to properly position it on the rod 54 or take up for wear. The numeral 63 denotes a by-pass in the cylinder 35 51 between and traversing the partitions 59 and 64. An orificed coupling member 123, having an adjusting-screw 124 to vary the area of its passage, delivers compressed air into the compartment containing the valve-head 61, and communicates with the air-supply pipe 117 by means of a communicating pipe 122, coupling 121, pipe 120, coupling 119, pipe 118, and coupling 116.

Referring to Fig. 1, I have shown herein 40 means for automatically actuating the apparatus at desired positions, such as the vicinity of highways, when it is desired to relieve the engineer entirely of the responsibility of actuating said whistle signal when approaching said highways. The numeral 45 50 96 denotes a valve chamber containing a check-valve 92, the latter having a channeled stem projecting at 97 from the chamber downwardly. This chamber 96 effects occasional communication between a conduit 55 consisting of a coupling 95, pipe 94, coupling 93, pipe 110, coupling 114, pipe 115, and coupling 116 to supply-pipe 117. Another conduit communicates between the chamber 60 65 96 and the other side of said chamber 90 by means of the coupling 98, pipe 99, coupling 100, and pipe 101.

A bracket support 102 below the chamber 96 has a spring barrel 103, and a plunger-rod 65 106 has a plunger 105 fixed thereon both

seated in the barrel 103, and a coiled spring 104 is mounted about said rod 106 and engaged between the orificed upper end of the barrel and said plunger-head. Said rod 106 is alined with the valve-stem 97 vertically, 70 and the lower end of the rod is forked to seat an anti-friction roller 107. The numeral 108 denotes part of an inclined-end block supported on cross-ties 109 within the path of forward translation of the roller 107. 75

Both the toothed head 34 and said rock-body 19 are loosely mounted on the rock-shaft 20, but the head 34 is, as already described, retained in an adjusted position fixedly by means of the dentated plate 127. 80 The rock-body 19 is connected fixedly, yet adjustably, to said rock-shaft by the following described means:

Referring to said Fig. 1, the numeral 47 denotes a disk fixedly mounted upon the 85 outer end of said rock-shaft and its circumferential edge is partially dentated at 48. A plate 39 is secured to the rock-body 19 by means of screws 49 and when the screws are removed, end-teeth 50 on said plate may 90 be meshed adjustably with any of the teeth on the disk 47. It will be seen that this adjustable connection of the rock-body 19 to the rock-shaft has the result of correspondingly varying the length of reciprocation of 95 the piston 85 and cylinder 80 or in fact, varies the distance through which the rock-body rocks. When such distance is shortened, for instance, the rock-body moves at greater speed so that the impulses produced 100 by the projections 21 to 24 inclusive upon the contact device 73—74 are shorter producing relative shortening of the whistle blasts.

To operate the device, the operator rocks 105 the handle 111 forward and back, such forward movement placing the valve in the chamber 112 to effect communication from the supply pipe 117 to the chamber 90 while cutting off the exhaust opening 113. Air under pressure is thus passed through the check-valve chamber 90 shifting the valve therein and then passing into the cylinder 80 through the passage 81 to force the piston 85 a stroke to the right. This compresses 115 the spring 87 while simultaneously the connecting rod 42 rocks the rock-body 19 upwardly to the right causing the projections thereon to successively lift and pass by the swinging arm 74 of the contact device without rocking the depending arm 73. As the arm 111 is rocked back by the operator communication between the pipe 117 and the chamber 90 is cut off, and the passage in the valve placed in registration with the exhaust-port 113 in the chamber 112 whereby 120 the compressed air in the cylinder and the pipes leading thereto is exhausted through said port. As in the rocking of the rock-body 19 upwardly the spring 81 becomes 125 130

placed under tension, when air pressure is released, the spring reacts and said rock-body is rocked back to its initial position causing its projections 21 to 24 inclusive to 5 successively engage the roller 78 and pushing down the arm 74 whose engagement with the stop 76 rocks the depending arm 73. Simultaneously, the upright arm 70 presses upon the contact-head 52 thrusting the 10 alined contacting rods 54 and 9 to the left compressing the interior spring 62 while the piston 65 compresses the other spring 66 in moving toward the left. Air-pressure is relayed into the cylinder 51 as follows:

15 When the rod 54 is pushed in by the arm 70, the port 55 becomes closed, and the rod 54 engages the end of the rod 57, closing the hollow of said rod 54 while the valve 61 opens the port 60, and as the air pressure in 20 the conduit 123 is constant, the air in the middle chamber in communication therewith passes through the port 60 and the by-pass 63 into the left-hand portion of the cylinder forcibly pushing the piston 65 and its 25 rod 9 with the connecting-rod 4 to rock the lever 3 and sound the whistle.

At each interval of said actuations when the contact-arms 74 are released the rod 54 is pushed outwardly by the compressed air 30 to the left of it, the cylinder-spring 62 reacts to return said piston 65 closing the valve 61, the air exhausting from the cylinder by way of the by-pass 63 and rod-passage 55 to the atmosphere. The action of 35 this device causes each blast of the whistle to begin and terminate quickly, while the blast is throughout from beginning to end maintained steadily and unvaryingly without tremors or increasing and decreasing volume 40 as normally the case when a whistle signal is merely manually operated.

Where entirely automatic actuation of the signal is desired and the additional equipment shown in Fig. 1 is combined with the 45 other equipment, the engineer's operating valve is kept closed. The check-valve 92 in the chamber 96 is normally kept on its seat by air-pressure thereabove and by a small coiled spring engaging it. The valve is lifted by the means hereinbefore described 50 when the roller 107 passes over and is shifted upwardly by the block 108, allowing passage of the compressed air into the pipes 99 and 101 leading to the right-hand end of the 55 valve-chamber 90 to shift the two-way check-valve therein to pass the air into the cylinder 80, operating its piston 85 in the method heretofore given. As the depending stem 97 of the valve 92 has a longitudinal 60 passage which opens through the side into the lower compartment of the valve-chamber 96, this passage being of relatively small size, when the valve 92 again closes said passage serves to exhaust the air from the 65 cylinder 80.

While the engineer's valve-chamber 112 is positioned as shown for manual operation, it is obvious that a similar valve may be used for pedal operation at another location by including it in another line of piping 70 serving as a by-pass. This will render the operation convenient under all circumstances.

Having described my invention, what I claim as new and desire to secure by Letters Patent, is:

1. In a signal governing apparatus, a signaling device having a movable operating element, a rock-body having projections, a contact-device connected operatively to said operating element and actuated by the projections on said rock-body with step-by-step movements to operate the signaling device with certain durations of actions separated by certain durations of intervals, a motor 80 operating for occasional actuations by the admission thereto of a fluid under pressure and adjustable connections between said motor and said rock-body for varying the speed of movement of said rock-body to vary the 85 durations of said actions and intervals of actions of the signaling-device.

2. In a signal governing apparatus, a signaling device having a movable operating element, a body having spaced projections, 95 a resilient element connected to said body yieldingly to return it when moved in one direction and then released, means for varying the degree of tension of said resilient element, and a contact-device connected 100 operatively to the operating element of said signal, to be engaged with and moved by said projections to operate the signal with intermittent action only while the said body is reactively moving back by impulsion of 105 said resilient element after being positively moved in one direction and then released.

3. In a signal governing apparatus, a signaling device having a movable operating element, a resiliently-controlled rock-body having a number of spaced circumferential cam-detents, a contact-device having a stop and a pivoted finger part positioned in the path of movement of said cam-detents to be shifted idly thereby while the rock-body is rocking in one direction and to be engaged by said detents and stop to oscillate the contact-device when the rock-body is rocked in a reverse direction, operative connections between said contact-device and the operating element of said signal, fluid-pressure controlled means connected to said rock-body, and means operable to initiate and terminate the action of the fluid-pressure controlled means.

4. In a signal governing apparatus, a signaling device having a movable operating element, a resiliently-controlled rock-body having a number of spaced circumferential cam-detents, a contact-device having a stop 130

- and a pivoted finger part positioned in the path of movement of said cam-detents to be shifted idly thereby while the rock-body is rocking in one direction and to be engaged 5 by said detents and stop to oscillate the contact-device when the rock-body is rocked in a reverse direction, operative connections between said contact-device and the operating element of said signal, fluid-pressure controlled means including a yieldable resilient reaction element connected to said rock-body, and means operable to initiate and terminate the action of the fluid-pressure controlled means. 10
- 15 5. In a signal governing apparatus, a signaling device having a movable operating element, a resiliently-controlled rock-body having a number of spaced circumferential cam-detents, means for varying the speed of 20 movement of said rock-body, a contact-device having a stop and a pivoted finger part positioned in the path of movement of said cam-detents to be shifted idly thereby while the rock-body is rocking in one direction 25 and to be engaged by said detents and stop to oscillate the contact-device when the rock-body is rocked in a reverse direction, operative connections between said contact-device and the operating element of said signal, fluid-pressure controlled means including a yieldable resilient reaction element connected to said rock-body, and means operable to initiate and terminate the action of the fluid-pressure controlled means. 30
- 35 6. In a signal-governing apparatus, a signaling device having a movable operating element, a resiliently-controlled rock-body having a number of spaced circumferential cam-detents, means for varying the degree 40 of tension of the resiliently-controlled rock-body, other means for varying the speed of rotation of said rock-body, a contact-device having a stop and a pivoted finger part positioned in the path of movement of said cam-detents to be shifted idly thereby while the rock-body is rocking in one direction and to be engaged by said detents and stop to oscillate the contact-device when the rock-body is rocked in a reverse direction, operative 45 connections between said contact-device and the operating element of said signal, fluid-pressure controlled means including a yieldable resilient reaction element connected to said rock-body, and means operable to initiate and terminate the action of the fluid-pressure controlled means. 50
- yieldable resilient reaction element connected to said rock-body, and means operable to initiate and terminate the action of the fluid-pressure controlled means. 55
7. In a signal governing apparatus, a signaling device having a movable operating element, a resiliently-controlled rock-body having a number of spaced circumferential 60 cam-detents, a contact-device having a stop and a pivoted finger part positioned in the path of movement of said cam-detents to be shifted idly thereby while the rock-body is rocking in one direction and to be engaged 65 by said detents and stop to oscillate the contact-device when the rock-body is rocked in a reverse direction, operative connections between said contact-device and the operating element of said signal, fluid-pressure controlled means connected to said rock-body, and means operable to initiate and terminate the action of the fluid-pressure controlled means, including a valve-chamber containing a check-valve having a projecting valve- 70 stem, and a resiliently-controlled movable contact-device propellable to open said check-valve and to react when released to allow the check-valve to close. 75
8. In a device of the character described, 80 the combination with a signaling-device, of a resiliently controlled rocking element having a number of different length and differently spaced cam projections, a jointed contact-device adapted to be operatively engaged and oscillated by said projections only while the rocking element is moved in one direction, operative connections between said contact-device and said signaling-device including a relay-device for receiving 85 and communicating fluid-pressure to operate the signaling-device with intermittent impulses like impulses given by said projections to the contact-device, and a fluid-pressure device operatively connected to said 90 rocking element to tensionally rock it in one direction, and including a valve-chamber and a controller-valve therein for communication with a source of fluid pressure, said chamber and valve having exhaust-passages 95 for registration when the valve is closed. 100

Signed at Waterloo, Iowa, this 16th day of Jan. 1922.

ALBERTO I. WOODRING.
